(57) **CLAIM**

We claim the ornamental design for a disinfection device for a valve, as shown and described.

DESCRIPTION

FIG. 1 is a top plan view of a disinfection device for a valve showing our new design;

FIG. 2 is a bottom plan view thereof;

FIG. 3 is a left side elevation view thereof;

FIG. 4 is a right side elevation view thereof;

FIG. 5 is a top perspective view thereof; and,

FIG. 6 is a top perspective view thereof shown in use with a valve.

The evenly spaced broken lines shown in the drawings depict portions of the disinfection device for a valve and environmental subject matter that form no part of the claimed design.
